UNITED STATES PATENT OFFICE

HARTVIG P. SAUGMAN, OF GLENDALE, CALIFORNIA

BEVERAGE DISPENSER

Application filed December 10, 1927. Serial No. 239,080.

This invention has to do with a beverage dispenser and has particular reference to that type of dispenser in which there is an ice container for cooling the beverage to be dispensed.

It is a general object of this invention to provide an effective, improved and practical dispenser of the character mentioned.

This invention has to do, generally, with that type of dispenser in which there is a main receptacle, for instance, a glass jar, for carrying the liquid to be dispensed, and an inner receptacle for carrying ice, or other cooling means, arranged within the main receptacle. Dispensers of this general type have had certain undesirable features, for instance, the inner or ice receptacle has been used as an agitator for the beverage to be dispensed, and to this end has been provided with fins or projections which are unsightly and generally undesirable. Further, devices of this nature have heretofore involved more or less complicated and unsatisfactory means for mounting the inner or ice container within the main container, and for obtaining operation of the inner container within the outer container.

It is a primary object of this invention to provide an inner or ice container for a dispenser of the character mentioned, which is effective in agitating liquid carried in the outer receptacle without requiring agitating fins, ribs, or other specially provided means.

Another object of this invention is to provide an improved and effective means for supporting an ice container within an outer container.

It is another object of this invention to provide a simple, practical and inexpensive means for operating or rotating an ice container within a main container.

The various objects and features of the invention will be best and more fully understood from the following detailed description of a typical form and application of the invention, throughout which description I will refer to the accompanying drawings, in which

Fig. 1 is a vertical detail sectional view of a device embodying the invention, Fig. 2 is a reduced transverse sectional view of the de-

vice, being a view taken as indicated by line 2—2 on Fig. 1, and Fig. 3 is a reduced transverse sectional view taken as indicated by line 3—3 on Fig. 1.

The device provided by this invention includes, generally, a main or beverage container 10 provided with a removable cover 11, an ice container 12 to be arranged in the beverage container 10, a mounting 13 for supporting the ice container 12 within the beverage container 10, and operating means 14 whereby the ice container can be rotated from the exterior of the cover 11.

The beverage container 10 may be in the form of an open top jar and is preferably formed of glass that may be pebbled, or otherwise finished, to be attractive in appearance. In accordance with my invention, I provide an upwardly or inwardly extending conical bottom 15 in the container 10 having its apex concentric with the central vertical axis of the container 10. For the purpose of dispensing the fluid or beverage from the container 10, I provide an opening 16 at, or adjacent, the bottom of the container, which opening may be fitted with a control valve 17, or the like. The conical bottom 15 is easily cleaned and when the outlet opening 16 is located as shown in the drawings, it makes it possible to discharge practically all of the liquid from the container through the valve. In practice, I provide a base 18 for supporting the container 10. The base 18 may be formed of metal and may be provided with a bead or rim 19 operable to hold the container 10 in position.

The cover 11 provided for the container 10 may be of suitable ornamental design, it being preferred in practice to provide a cover that is more or less concavo-convex in shape and mounts on the container 10 to project above the top of the container. In practice, I find it convenient to form the cover of metal and to fit it over the upper end of the container 10, as clearly illustrated in Fig. 1 of the drawings.

The ice container 12 provided by my invention is somewhat smaller in diameter than the beverage container 10, so that it will fit within the container 10 with substantial clear-

ance, as illustrated in the drawings. The container 12 is made sufficiently long or tall to extend to the top, in fact, preferably above the top, of the container 10 when in operating position. In accordance with my invention, I make the ice container 12 polygonal in cross sectional configuration, for instance, square, as illustrated in Fig. 2 of the drawings. In practice, the corners of the container 12 are slightly rounded. In the preferred form of the invention, the ice container 12 is made of metal and is finished, particularly on its exterior, with porcelain enamel, or the like, so that it can be readily cleaned and will remain comparatively clean, under ordinary conditions of use.

The mounting 13 provided for supporting the ice container 12 in the beverage container 10 includes a body of rubber, or the like, applied to the lower end of the container 12 and provided with a central downwardly facing socket 30 to receive the apex of the conical bottom 15 of the container 10 and with guide ribs 31 which operate to guide the container 12 into central position in the container 10, and to brace it in an upright position. In practice, I prefer to form this mounting member of rubber, or the like, for by so doing it presents or acts as a bumper for relieving impact between the containers when the ice container is lowered into the beverage container. Further, by forming the mounting member of rubber, it can be very easily applied to the lower end of the ice container. In the preferred construction, the mounting member is provided at its upper side with an upwardly facing socket 35 which tightly receives the lower end of the ice container in the manner clearly shown in Fig. 1 of the drawings. When the mounting member is applied to the lower end of the ice container, it will remain in place until deliberately removed. The socket 30 is centrally located and shaped to receive the apex of the conical bottom 15 of the container 10. The ribs 31 which may be varied in number, size and proportion, may be disposed radially and may have their lower edges 36 shaped to normally just clear the bottom of the container 10.

The operating means 14, whereby the ice container 12 may be rotated from the exterior of the cover 11, may include an operating knob 40 centrally located at the exterior of the cover 11, a spindle 41 extending from the knob through the cover 11, and a driving bar 42 carried by the spindle 41 at the interior of the cover 11 to engage and drive the container 12. In the preferred construction, I provide a hollow knob 40 and arrange a coil spring 43 within the knob having one end attached to the spindle 41 and the other end attached to the cover 11. With this arrangement, manual rotation of the knob 40 in one direction will cause rotation of the container

12 and winding of the spring, so that the spring will cause rotation of the container 12 in the opposite direction, upon the knob being released. The operating bar 42 may be carried by the lower end of the spindle 41 to fit diagonally into the top of container 12 to have a driving engagement therewith. The ends of the bar may be upturned and may be covered with rubber, or the like, as shown in the drawings.

During normal operating conditions, the ice container 12 carrying ice is arranged in the beverage container 10 in the position shown in Fig. 1. The beverage in the container 10 is surrounding the ice container is cooled by the ice within the container 12. When dispensing certain beverages, it is desirable, in fact, in some cases necessary, to occasionally agitate the beverage. To do this, the operator turns the operating knob, causing rotation of the ice container. The ice container 12, because of its formation, that is, because of its polygonal cross sectional configuration, effectively agitates the beverage within the container 10, when rotated. The mounting member supports the container 12 in the container 10 so that it is easily rotated, and being of rubber in the presence of a liquid, allows the container 12 to turn with very little friction. When the cover 11 is removed, the operating means for the container 12 is removed with it, thus leaving the container 12 unrestricted for the introduction of ice, or the like. When the cover is returned to position, the operating bar can be readily introduced into the diagonal position in the top of the container 12 by rotation of the knob until the bar reaches the diagonal position with reference to the container. When the device is being handled, that is, upon the parts being assembled, the mounting member on the bottom of the ice container 12 being of rubber, forms an effective bumper for relieving impact between the container 12 and the bottom of the container 10, so that the bottom of the container 10 is not broken in case container 12 is lowered too fast. Further, the ribs 31 cooperate with the conical bottom of container 10 to guide or centralize the container 12 in the container 10, and act more or less to brace or support the container 12 in an upright position in the container 10.

In practice a weight 70 may be provided in or at the bottom of the ice container to retain it in an upright position. Further suitable markings or graduations may be provided on the container 10 to facilitate proportioning liquids or materials to be mixed to form a beverage to be dispensed.

Having described only a typical preferred form of my invention I do not wish to limit myself to the specific details set forth, but wish to reserve to myself any changes or variations that may appear to those skilled in

the art or fall within the scope of the following claims.

Having described my invention, I claim:

5. A dispenser of the character described, including a main liquid container, an ice container, and a mounting member for rotatably supporting the ice container in the main container, the mounting member being formed of resilient material and having a central part for engaging the bottom of the main container and ribs around the central part.
10. A dispenser of the character described, including a main liquid container, an ice container, and a mounting member for rotatably supporting the ice container in the main container, the mounting member being formed of resilient material and having a central part for engaging the bottom of the main container and a plurality of guide ribs 20 extending radially with reference to the central part.

15. A dispenser of the character described, including a main liquid container having an upwardly extending conical bottom, an ice container to be arranged in the main container, and a mounting member for rotatably supporting the ice container in the main container having a part holding the ice container and having a central socket to receive 25 the bottom of the main container.

20. A dispenser of the character described, including a main liquid container having an upwardly extending conical bottom, an ice container to be arranged in the main container, and a rubber mounting member for rotatably supporting the ice container in the main container including a central socket 35 to receive the bottom of the main container.

25. A dispenser of the character described, including a main liquid container, a cover for said container, an ice container mounted in the main container for rotation, and means for rotating the ice container from the exterior of the cover including an operating member at the exterior of the cover, a spindle connected with the member and extending through the cover, and a bar carried by the spindle to extend into the top of the ice container.

30. 6. A beverage dispenser of the character described, including a main liquid container, means for dispensing liquid from the container, a cover for said container, an ice container substantially square in cross sectional configuration and mounted in the main container for rotation, and means for rotating the ice container from the exterior of the cover including an operating member at the exterior of the cover, a spindle connected 35 with the member and extending through the cover, and a part carried by the spindle to releasably engage the ice container to rotate with the spindle.

35. 7. A dispenser of the character described, including a main liquid container, a cover

for said container, an ice container mounted in the main container for rotation, and means for rotating the ice container from the exterior of the cover including an operating member at the exterior of the cover, a spindle connected with the member and extending through the cover, a spring connected between the spindle and cover and carried in the operating member for rotating the spindle, and a part carried by the spindle to extend into the ice container to releasably engage the ice container to rotate with the spindle.

8. A dispenser of the character described, including a main liquid container, a cover for said container, an ice container mounted in the main container for rotation, and means for rotating the ice container from the exterior of the cover including a hollow operating member at the exterior of the cover, a spindle connected with the member and extending through the cover, a spring connected between the spindle and cover and carried in the operating member for rotating the spindle, and a part carried by the spindle to releasably engage the ice container to rotate with the spindle.

9. A beverage dispenser of the character described including, a main liquid container, an ice container to be arranged in the liquid container, and a rubber mounting member supporting the ice container in the liquid container, there being radially extending ribs on the bottom of the mounting member.

10. A beverage dispenser of the character described including, a main liquid container, an ice container to be arranged in the liquid container, and a rubber mounting member supporting the ice container in the liquid container, the mounting member having a part fitting around the lower portion of the ice container and having radially extending ribs on its lower side.

11. A beverage dispenser of the character described, including a main liquid container, means for dispensing liquid from the main liquid container, an ice container of polygonal cross-sectional configuration, and a mounting member for rotatably supporting the ice container in the main container, the mounting member being formed of rubber.

In witness that I claim the foregoing I have hereunto subscribed my name this 29th day of July 1927.
